UNITED STATES PATENT OFFICE.

WILLIAM H. ODLUM, OF CHICAGO, ILLINOIS, ASSIGNOR TO DURO METAL PRODUCTS COMPANY, OF CHICAGO, ILLINOIS, A CORPORATION OF ILLINOIS.

VAPORIZING DEVICE.

Application filed May 10, 1928. Serial No. 276,549.

The present invention relates to vaporizing devices and is particularly concerned with devices adapted to be used both as a humidifier and as a vaporizer for disinfectants, perfumes, etc. The vaporizer which forms the subject matter of the present invention is of the general type employing an incandescent electric light bulb as a heating element with or without a periodic switch for lighting the bulb at regular intervals. In the vaporizers of the prior art, the bulb socket, electric conductors and periodic switch are usually located in the base of the device, with the bulb projecting upward through a tubular portion of the reservoir, and much trouble and inconvenience has been caused by the leaking of the fluid to be vaporized, down into the electric connections and coils of the periodic switch, short circuiting the lamp and coils, with the possibility of blowing fuses and causing other electrical trouble.

One of the objects of the present invention is the provision of an improved vaporizer structure in which the heating element is supported in inverted position with the socket, coils and connections located above the reservoir, thereby avoiding the possibility of short circuiting electrical connections.

Another object of the invention is the provision of a novel vaporizing device which may be employed both as a humidifier and as a vaporizer for disinfectants, deodorizing compounds, etc. and in which the electrical conductors are enclosed and protected from short circuit by the liquid to be vaporized.

Another object of the invention is the provision of an improved vaporizer casing which is adapted to enclose the operating elements of the vaporizer and to reflect the radiated heat of the lamp toward the fluid to be vaporized, thereby increasing the efficiency of operation of the device.

Other objects and advantages of the invention will appear more fully from the following description and from the accompanying drawings, in which similar characters of reference apply to similar parts throughout the several views.

Referring to the drawings, of which there

Fig. 1 is an elevational, cross-sectional view, with the casing partially broken away to show the interior structure of the vaporizer;

Fig. 2 is an elevational, cross-sectional view, partially broken away, taken on the line 2—2 of Fig. 1;

Fig. 3 is a cross-sectional view of the socket and periodic switch taken on the line 3—3 of Fig. 2;

Fig. 4 is a side elevational view taken from the left in Fig. 2;

Fig. 5 is a bottom plan view of the socket and periodic switch.

Referring to Figs. 1 and 2, 10 indicates in its entirety my vaporizer casing which comprises a base 11, a reservoir 12 and a cover 13. The vase 11 comprises a stamped sheet metal member of substantially cup shape, having a flat top 14 and a curled lower edge 15.

The vase is provided with a plurality of apertures 16 one of which may be employed for admitting the conductors 17 and 18 through a rubber bushing 19.

The top 14 of the base is provided with a centrally located aperture 20 adapted to register with a tubular wall or enclosure 21 formed within the reservoir 12. The reservoir 12 may also consist of a stamped sheet metal member having the inner tubular wall 21 and an outer substantially cylindrical wall 22 forming the annular chamber or reservoir 12 for the fluid to be vaporized.

The outer cylindrical wall 22 may curve inward as at 23 and downward as at 24 to unite with a flat annular bottom 25 of substantially the same size as the top 14 of the base 11. The reservoir 12 and the base 11 may be secured together by a plurality of rivets 26 passing through the top 14 of the base and the bottom 25 of the reservoir, the rivets being soldered within and without the reservoir in order to insure against leakage.

The cylindrical wall 22 of the reservoir may be bent outward as at 27 and formed with a cylindrical portion 28 of slightly larger diameter adapted to receive the cylindrical flange 29 of the cover 13.

The cover 13 may comprise a substantially cup-shaped, stamped sheet metal member

having a cylindrical outer wall 30 which is provided with a plurality of rows of apertures 31 adapted to permit the escape of vapors from the fluid within the reservoir 12 and the upper portion of the cover may be curved as at 32 and 33 forming a substantially dome-shaped cover with an ornamental bead 34. The apertures 31 are preferably so located that the cover substantially conceals the socket 35 and other mechanism of the vaporizer, but permits a view of the bulb 36 which is periodically lighted and extinguished, thereby drawing attention to the device.

15 At its lower edge, the cover 13 is formed with a bead 37 which is adapted to limit the inward movement of the flange 29 within the reservoir 12.

Carried by the base 11 is a tubular standard 38 which may be secured to the base by passing through apertures 39 in both the base and the reservoir, and by being provided on either side of these parts with a nut 40. The joint about the nuts 40 may be sealed by soldering 20 both above and below the reservoir and the standard 38 is thus adapted to provide a closed conduit for the conductors 18 and 19 from beneath the base 11 up through the reservoir 12.

30 At its top, the standard 38 is adapted to support a yoke 41 which may be constructed of cast metal having a bore 42 adapted to receive the tubular standard 38 and having a pair of legs 43 extending in substantially semi-circular form to provide a support for the socket 35. The yoke 42 may be secured to the standard 38 by a pin 44 riveted in the yoke 41 and extending into a slot 45 at the top of the tube. The pin 44 effectively prevents rotation between the yoke and the standard and prevents the yoke from sliding down upon a standard, but it also permits the socket to be lifted from the standard 38 when necessary for the purpose of repairs or otherwise.

40 The socket 35 comprises a cylindrical body 46 of porcelain or other insulating material formed with an integral insulating base 46 having outwardly projecting lugs 47, 48, 49 and 50 for the purpose of supporting 45 electrical connectors and other parts. The socket is provided with the usual central bore 51 which is adapted to receive a pressed sheet metal member 52 formed with screw threads and adapted to receive the threaded base of 55 the bulb 36.

The threaded member 52 is provided with a pair of inwardly extending annular flanges 53 which are in electrical contact with legs 54 of the substantially semi-circular metal plate 55. The body of the socket 35 is provided with an aperture 56 and the metal plate 55 is provided with an outwardly extending arm 57 having a threaded aperture adapted to receive a screw bolt 58 and having an upwardly extending lip 59 forming an electrical

connector, to which one of the conductors 17 may be secured.

The base 46 of the socket body is also provided with a centrally located bore 60 which is counter-sunk as at 61 to receive the head 70 and stem of a screw bolt 62 which is adapted to project into the interior of the socket forming a central contact member and securing a bi-metallic thermal strip 63 by means of a nut 64.

75 The bi-metallic strip 63 comprises a pair of sheets of metal having different co-efficients of linear expansion, such as steel and brass, and secured together by means of the bolt 62 and the contact 65 riveted therein. The bi-metallic strip is covered with a layer of head resistive insulating material upon which are wound a plurality of coils 66 of resistance wire, one end of the resistance wire being connected to the center contact bolt 62 and the other end being connected by a pigtail 67 to a contact bridge 68.

80 The contact bridge 68 comprises a short strip of sheet metal bent to substantially U-shape and having outwardly extending feet 90 69, one of which is employed for securing the bridge to the socket body 46 by means of a screw bolt 70, and the other of which is employed as an electrical connector by means of the screw bolt 71 threaded therein. The connectors 69-71 are secured to the other conductor 18 and the contact bridge 68 is provided with a threaded aperture adapted to receive a threaded screw bolt 72 directly opposite the contact 65 upon the bi-metallic element.

95 The screw bolt 72 is provided with a lock nut 73 for retaining the contact in adjusted position.

100 The electrical circuits for my vaporizing device may then be traced as follows. Both the supply conductors 17 and 18 are brought in at the rubber bushing 19 in the base 11, passing upward through the tubular standard 38 where the braided covering is split 110 and the wires 17 and 18 are secured to the connectors 58 and 71 respectively.

115 From the connector 58 one of the supply conductors is in communication with the threaded portion 52 of the socket by means of the metal plate 55 and the circuit continues through the filament of the bulb 36 down to the center contact 62. The center contact 62 is connected with one end of the heater coil 66 and the opposite end of the heater coil 66 is 120 connected to the contact bridge 68 which is connected with the contact 71 and the other supply conductor 18.

125 It will thus be observed that the heating coils 66 are connected in series with the lamp and the coils and lamp will be energized at all times. However, the resistance of the coils is such that the current passing through the circuit just described will not be sufficient to heat the lamp to incandescence, and the 130

lamp will not emit any light during such connection.

It will also be observed that the bi-metallic strip 63 is connected to the center contact 62 and when this strip has been heated by means of the heater coil 66, it will be bent in such manner as to close the contacts 72 and 65, thus establishing a connection which will short circuit the coil 66 and permit the full voltage 10 to be impressed upon the lamp 36. The lamp will then be lighted but due to the short circuiting of the coils 66, practically no current will flow through the heater coils and the bi-metallic strip will cool until it resumes the 15 position shown in Fig. 3, again breaking the contact at 65, 72, after which the foregoing cycle of operations will be repeated.

The projecting lugs 47 and 49 upon the porcelain body 46 are provided with apertures 74 adapted to receive screw bolts 75 which pass through a cover plate 76 and through the legs 43 of yoke 41. The porcelain body is then secured to the yoke 41 by means of the nuts 77 with the open end of the 25 socket extending downward to support the bulb 36 within the enclosure 21 of the reservoir. The bulb is preferably supported out of contact with the walls of the reservoir, in order that heat may be conducted uniformly 30 from all parts of the bulb, and although any type of bulb may be employed, an elongated cylindrical bulb of the type shown is preferred.

The inner wall 21 of the reservoir 35 rounding the bulb 36 also carries a perforated sheet metal member 78 of substantially cylindrical form and adapted to provide a support for a wick 79 comprising a strip of highly absorbent thick cotton fabric having its ends 40 sewed together to form a tubular member fitting about the frame 78.

The operation of my vaporizer is as follows. The liquid to be vaporized is placed in the annular reservoir 12 where it covers the 45 lower end of the wick 79 which surrounds the bulb 36. When the conductors 17—18 are connected to a source of electromotive force, the lamp 36 is alternately lighted and extinguished as previously described, and the relative 50 time during which the lamp remains lit may be determined by the adjustment of the set screw 72. The liquid will then be drawn up in the wick 79 by means of capillary attraction and the liquid in the wick will be 55 evaporated by heat radiated from the lamp 36. The cover 32 permits the vapors to pass out through the apertures 31, but substantially conceals the mechanism of the socket 35 and is adapted to reflect radiated heat toward 60 the liquid to be vaporized.

The periodic switch and electrical connections being located at the uppermost portion of the vaporizer and the conductors being 65 protected by the tubular standard 38, the danger of short circuit is minimized and my

vaporizer is capable of long and continuous use without any necessity for alteration or repair.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a vaporizer, the combination of a 80 supporting base with an annular reservoir carried thereby, a hollow standard in said reservoir, a lamp socket carried by said standard, and an electric bulb depending from said socket into a well in said reservoir. 85

2. In a vaporizer, the combination of a supporting base with an annular reservoir carried thereby, a hollow standard in said reservoir, a lamp socket carried by said standard, an electric bulb depending from said socket 90 into a well in said reservoir, and electric conductors connected to said socket and located in said standard.

3. In a vaporizer, the combination of a supporting base with an annular reservoir carried thereby, a hollow standard in said reservoir, a lamp socket carried by said standard, an electric bulb depending from said socket 95 into a well in said reservoir, and a perforated cover carried by said reservoir about said 100 socket.

4. In a humidifier, the combination of a base with an annular reservoir carried by said base, a cover for said reservoir, said cover having a plurality of perforations, a tubular 105 member carried by said base in said reservoir, an electric light socket carried by said tubular member, an electric heating element in said socket, and electrical conductors leading to said socket through said tubular member. 110

In witness whereof, I hereunto subscribe my name this 4th day of May, 1928.

WILLIAM H. ODLUM.
